THE NORRIS PETERS CO., PHOTO-LITHO., WASHINGTON, D. C.

UNITED STATES PATENT OFFICE.

NEWTON A. COOPER, OF WINCHESTER, VIRGINIA.

CAR-COUPING.

SPECIFICATION forming part of Letters Patent No. 564,973, dated August 4, 1896.

Application filed January 20, 1896. Serial No. 576,171. (No model.)

To all whom it may concern:

Be it known that I, NEWTON A. COOPER, a citizen of the United States, residing at Winchester, in the county of Frederick and State of Virginia, have invented a new and useful Car-Coupler, of which the following is a specification.

The invention relates to improvements in car-couplings.

10 The object of the present invention is to improve the construction of car-couplings and to provide one capable of coupling automatically and of being readily uncoupled without going between cars, and also to provide means for automatically coupling the 15 air-brake connections when two cars come together and for automatically cutting off the air when the cars are uncoupled.

The invention consists in the construction 20 and novel combination and arrangement of parts hereinafter fully described, illustrated in the accompanying drawings, and pointed out in the claims hereto appended.

In the drawings, Figure 1 is a perspective 25 view of a car-coupling constructed in accordance with this invention and shown applied to a car. Fig. 2 is a horizontal sectional view. Fig. 3 is a plan view. Fig. 4 is a longitudinal sectional view. Fig. 5 is a side elevation. Figs. 6 and 7 are detail views illustrating the construction of the air-pipe 30 couplings. Fig. 8 is a detail sectional view illustrating the construction of the cushion of the draw-bar.

35 Like numerals of reference designate corresponding parts in all the figures of the drawings.

1 designates a hook-shaped draw-head provided with a shank 2 and pivoted intermediate 40 of the ends thereof by a vertical pin 4 to a bracket 5, designed to be mounted on a car by means of stirrups or hangers and capable of a limited longitudinal movement. The bracket is provided with sides 6, and has secured to it beneath the shank of the draw-head a draw-bar 7, designed to be connected with any suitable cushion to take up the shocks and jars. The front end of the draw-bar is perforated to receive the pivot 4, and 45 is secured in rear of the shank of the draw-head by a vertical pin 8, mounted in perfor-

5 rations of the bracket and a cross-piece 9 at the bottom thereof.

The cushion of the draw-bar preferably consists of a cylinder 7^a, open at its outer end, 55 a piston-head 7^b, and a piston-rod 7^c, pivotally connected at its terminals to the piston-head and the rear or inner end of the draw-bar.

The draw-head is capable of swinging horizontally to couple automatically and is cushioned in its lateral movements and maintained in proper position to hold it in engagement with a corresponding draw-head by a pair of spiral springs 10, arranged within the bracket 65 and interposed between the sides thereof and the shank and located at the rear end of the latter.

The draw-head is connected with its shank by a knuckle-joint 11, and is arranged to 70 swing upward to effect the operation of uncoupling, and the operation of uncoupling is performed by means of a transverse rock-shaft 12, journaled in suitable bearings of a pivoted block 13, provided at its inner end 75 with an arm, and connected with the draw-head by a short chain. The outer end of the rock-shaft may be provided with any suitable form of handle, and any suitable means may be employed for enabling the operation 80 of uncoupling to be performed from the top of a car or the platform of a coach.

The pivoted block 13 is connected with the bracket by the vertical pivot 4, and it consists of an upper horizontal portion and depending vertical sides 15 and 16. The horizontal portion has its rear edge curved, and it is seated in a recess of the bracket to form a knuckle-joint, and shoulders 17 are provided at the terminals of the curved rear 90 edge to limit the swing of the pivoted block. The depending side 15 has a rounded outer or front edge 18, and the other side, 16, is provided at its front edge with a vertical recess 19, adapted to receive the curved edge 18 of 95 a corresponding coupling. The side 15 carries a male section 20 of an air-brake coupling or connection, and the side 16 carries a female section 21. The male section is mounted in suitable openings or perforations of the adjacent sides of the pivoted block and the brackets and projects from the former, and 100

is adapted to enter a socket 22 from the female section, whereby when two cars come together the air-brake connections will be automatically coupled.

5. Each air-brake-coupling section has a spiral spring 23 disposed on it and interposed between the adjacent sides of the bracket and the pivoted block; and each section of the air-brake connection is provided with a shoulder which is engaged by the front end of the companion spiral spring 23, whereby the section is normally held extended to maintain a stop-cock or cut-off 24 closed when a car is uncoupled. A stop-cock or cut-off 24 is mounted on each of the sections of the air-brake connection, and it is provided with a crank-arm arranged in a substantially X-shaped recess 25 of the pivoted block, whereby, when the sections of the couplings are reciprocated, incident to cars coupling and uncoupling, the cut-offs or stop-cocks will be automatically operated to open them when the cars couple, and to close them when the cars are uncoupled or separated.
25. The spiral springs 23 cushion the pivoted block and enable the same to yield to any movement on cars incident to the passage of a train over a rough road-bed and to prevent the sections of the air-brake connection from becoming accidentally uncoupled.

It will be seen that the car-coupling is exceedingly simple, inexpensive in construction, that it is positive and reliable in operation and capable of automatically coupling and of being readily uncoupled without going between cars, and that the air-brake connections are automatically coupled. It will also be apparent that the cut-offs or valves of the air-brake connections operate automatically and establish a communication between the cars when coupled and shut off the air when the cars are uncoupled, so that there is no leakage or loss of air.

Changes in the form, proportion, and the minor details of construction may be resorted to without departing from the spirit or sacrificing any of the advantages of this invention.

What I claim is—

1. In a car-coupling, the combination with a bracket or support, of a draw-head having a shank pivoted intermediate of its ends to the bracket or support, and capable of swing-

ing horizontally, said draw-head being connected with its shank by a hinged joint and capable of swinging upward to effect the operation of uncoupling, and cushions arranged at opposite sides of the shank in rear of the pivotal point, substantially as and for the purpose described.

2. In a car-coupling, the combination of a bracket, a shank disposed longitudinally thereof and pivotally connected therewith, a draw-head hinged to the front end of the shank and capable of swinging upward, cushioning-springs located at opposite sides of the shank in rear of the pivotal point, and a draw-bar connected with the bracket and extending rearwardly therefrom, substantially as described.

3. In a car-coupling, the combination of a bracket or support, a block pivotally connected therewith, a draw-head, air-brake connections disposed at opposite sides of the pivot of the block, and springs actuating the air-brake connections and cushioning the pivoted block, substantially as described.

4. In a car-coupling, the combination of a suitable support provided with a substantially X-shaped recess, a reciprocating pipe or section mounted on the support, and a cock or cut-off having an arm arranged in the said recess, substantially as and for the purpose described.

5. The combination of a bracket, a block pivoted to the bracket and comprising a horizontal upper portion having a curved rear edge arranged in a recess of the bracket and provided with shoulders to limit the pivotal movement, and depending sides, one of the sides being provided with a vertical recess, the air-brake pipes or sections disposed at opposite sides of the pivoted block and capable of a limited reciprocation, and springs mounted on the pipes or sections, actuating the same and forming cushions for the pivoted block, substantially as described.

In testimony that I claim the foregoing as my own I have hereto affixed my signature in the presence of two witnesses.

N. A. COOPER.
